UNITED STATES PATENT OFFICE.

ELWOOD B. AYRES, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Application filed May 9, 1922. Serial No. 559,558.

To all whom it may concern:

Be it known that I, Elwood B. Ayres, a citizen of the United States, residing in Philadelphia, Pennsylvania, have invented 5 certain improvements in Driers, of which the following is a specification.

My invention relates to certain improvements in driers for which application for patent was filed by E. C. Faber on the 6th 10 day of May, 1922, Serial No. 558,893.

In this drier, the material is mounted on a rotary carrier and the carrier is rotated while the material is subjected to currents of heated air.

15 The object of my invention is to construct a drier of the tunnel type, in which the material is carried through a drying compartment on cars, or other carriers, while being subjected to currents of air in such a manner as to provide means for rotating the material mounted on the cars as they pass through the drying compartment.

In the accompanying drawings:

Fig. 1 is a sectional plan view of a drier 25 illustrating my invention;

Fig. 2 is an enlarged sectional plan view on the line 2—2, of Fig. 3, showing the gearing by which the carrier is turned;

Fig. 3 is a transverse sectional view on 30 the line 3—3, Fig. 2; and

Figs. 4, 5 and 6 are views of modifications of the invention.

Referring to the drawings, 1 is the casing of the drier. 2, 2 are longitudinal partitions dividing the drier into three compartments *a*, *b* and *c*. *a* is the drying compartment and *b* and *c* are the heating compartments. In the latter compartments are steam coils 3, in the present instance. Other 35 means may be provided for heating the air, if desired. In each partition are openings 4 and 5 for the circulation of air. Each alternate opening 4 in each partition is designed to receive a circulating fan 6 mounted on a horizontal shaft, which is driven in any suitable manner. It will be noticed that the fans 6 on one side are opposite the openings 5 on the other side so that the heated air will circulate across the drying 40 compartment, as indicated by arrows in Fig. 1.

15 is a track on which cars 7 are mounted. These cars are arranged close together, in the present instance, so that, when one car 55 is pushed into the drying compartment, an-

other car is pushed out. The openings 8 in the ends of the drier are closed by suitable doors, not shown.

9 are rotatable carriers for the material to be dried. Each carrier is pivotally mounted on its car at 10, the pivot being adapted to suitable bearings on the car. The carriers can be constructed so that the material can be arranged in tiers, or in any manner desired, but the arrangement should be such as not to interfere materially with the free circulation of air in the drying compartment.

On each carrier 9 is a gear wheel 11, which meshes with the teeth of a fixed rack 70 12 at the side of the drying compartment.

As the cars are pushed forward, the rack—being fixed—causes the carriers to be turned so as to alter the position of the material in respect to the circulating fans. 75 This arrangement presents different surfaces to the direct action of the currents of air as the cars are traversed through the drying compartment, thoroughly drying the material mounted on the carriers.

In Fig. 4 a modification is illustrated, in which the pivot 10^a of the carrier 9^a extends through the car 7^a and has a pinion 11^a, which meshes with a rack 12^a between the rails of the track. This construction 80 will cause the carrier to turn a greater distance with the same movement of the car, as shown in Fig. 1. It will be understood that the rack may be placed at any convenient point, depending considerably upon 85 the type of car used for carrying the material to be dried.

In Fig. 5, rails 15^b are illustrated at each side of the drying chamber. The cars 7^b travel on these rails. Suspended from the 90 cars are carriers 9^b by the shaft 10^b, which has at its upper end a gear wheel 11^b, meshing with a fixed rack 12^b. A carrier, in this instance, has a series of platforms on which the material to be dried can be placed.

In Fig. 6, rails 15^c are shown suspended from the roof of the drying compartment. The carrier 9^c may be guided by a bottom rail 16, as shown. The gear wheel 11^c is secured to the shaft 10^c above the car 7^c 105 and meshes with the teeth on a rack 12^c secured to the roof.

I claim:

1. The combination of a drier having a longitudinal drying compartment; means 110

for circulating heated air in said compartment; cars arranged to travel through the compartment; a carrier mounted on each car; and means for imparting a rotary movement to the carriers as the cars travel through the compartment of the drier.

2. The combination of a drier having a longitudinal drying compartment; means for circulating heated air across the drying compartment; a longitudinal track in the drying compartment; a series of cars on the track; a rotatable carrier on each car; and means for rotating the carriers as the cars move longitudinally through the drying compartment.

3. The combination in a drier, of a longitudinal drying compartment; means for circulating air in the compartment; cars arranged to travel through the compartment; a carrier on each car; a gear wheel on each

carrier; and a fixed longitudinal rack with which the gear wheels engage as the cars are traversed through the compartment.

4. The combination in a drier, of a casing having two partitions separating the interior of the drier into three longitudinal compartments, the central compartment being a drying compartment and the side compartments being heating compartments; circulating fans located in the partitions so as to cause the air to circulate across the drying compartment; a longitudinal track in the drying compartment; a series of cars mounted on the track; a carrier on each car; a gear wheel on each carrier; and a longitudinal rack with which the gear wheels engage so that, as the cars are moved through the drying compartment, the carriers are turned.

ELWOOD B. AYRES.
